UNITED STATES PATENT OFFICE.

GEORGE B. SECHRIST, OF SHENANDOAH, OHIO, ASSIGNOR OF ONE-HALF TO
JOHN H. BURKHOLDER, OF ASHLAND, OHIO.

FENCE-STAY-FASTENING TONGS.

SPECIFICATION forming part of Letters Patent No. 586,697, dated July 20, 1897.

Application filed July 31, 1896. Serial No. 601,209. (No model.)

To all whom it may concern:

Be it known that I, GEORGE B. SECHRIST, a citizen of the United States, residing at Shenandoah, in the county of Richland and State 5 of Ohio, have invented certain new and useful Improvements in Fence-Stay-Fastening Tongs; and I do hereby declare the following to be a full, clear, and exact description of the invention, such as will enable others skilled 10 in the art to which it appertains to make and use the same.

My invention relates to means for securing stays to fence-wires, its object being to secure a better fastening and simplify and cheapen 15 the application thereof; and it consists in the improved apparatus for applying a specially-formed fastener to the stay-wire of fences, as hereinafter described.

In the drawings, Figure 1 is a view in front 20 elevation, Fig. 2 a side elevation, and Fig. 3 a top plan view, of the fastener as it appears when fastened in place upon the fence-wire and stay. Fig. 4 is a perspective view, and Fig. 5 a side elevation, of the fastener before 25 it is applied to the fence. Fig. 6 is a top plan view of the clenching-tongs by means of which the fastener is applied to the fence, and shows the fastener in place. Fig. 7 is a plan view of the under side of the tongs. Fig. 8 is an end view of the tongs with their 30 jaws open. Fig. 9 is a like view with the jaws closed, and Fig. 10 is a side view of the jaws.

A represents the tongs; B, the fence-wires; b, the stay-wires crossing the same; C, the fastener; c c', the free ends thereof, which lie in different planes, as seen in Fig. 5 and in dotted lines in Fig. 2, the bends c³ and c⁴ being formed near these ends to embrace one of the stay-wires b of the fence, and c² being 35 the middle bend or bight to engage one of the main wires B of the fence, as seen in Figs. 3 and 4.

The tongs A comprise the arms or handles a a', pivoted at f and terminating in jaws 40 which on one side are provided with projections d d', which nearly or quite meet in the middle line, as seen in Fig. 6, and which I call the "upper" side of the tongs for the reason that in placing the fastener C upon the wires 45 it is usually hooked on from above instead of from underneath, and thus brings the bight

c² uppermost, although it is obvious that the fastener can be placed either side up or with the bight c² vertical instead of horizontal, if preferred. The opposite or lower sides of the 55 jaws are provided with projections e e', respectively, which are separated from the jaws d d' by a deep groove or slot, into which the fence or stay wire is received, as seen in Figs. 6 and 10, and which shut past each other, as 60 seen in Figs. 8 and 9, and in so doing catch the projecting free ends c c' of the fastener and bend them closely and snugly around the wire to the position shown in Figs. 1 and 2, in which it will be seen that no projecting 65 ends are left on either side of the fence, but a smooth, rigid, and extremely neat finish is produced. By so shaping the jaws that their internal opening is narrower at the back, as seen in Figs. 6 and 7, the two hooks or bends 70 c³ c⁴ of the fastener C may be squeezed more or less together when the jaws are completely closed, as seen in Fig. 6, which tends to draw the fastener more tightly upon the wires and to more firmly bind the stay-wire and fence-wire together. It is preferable, although not 75 strictly necessary, to slightly groove the ends of the jaws e e', as shown, which causes them to more readily and certainly catch and guide the free ends c c' of the fastener in bending 80 them.

By the use of this tongs or special tool the fastener can be grasped and pinched to its finished position with a single motion of the hand and in less than one-twentieth of the 85 time required to twist a fastener in place. To enable this to be done, it is important that the two free ends of the fastener should lie in different planes when the tongs are applied, or otherwise they would meet when the tongs 90 closed and would not only prevent the complete closing of the tongs, but would project from the fence and possibly cause injury to stock.

Having fully described my invention, what 95 I claim, and desire to secure by Letters Patent, is—

1. The clenching-tool for wire-fence-stay fasteners above described, comprising the pivoted arms having jaws which meet in the 100 central line, and bending-jaws separated therefrom by a slot and which are shouldered

and shut past each other to bend and clench the ends of the fastener, substantially as described.

2. The clenching-tool for wire-fence-stay fasteners above described, comprising the pivoted arms having jaws which meet in the central line, and grooved bending-jaws separated therefrom by a slot and which are shouldered and shut past each other to bend

and clench the ends of the fastener, substantially as described.

In testimony whereof I hereto affix my signature in presence of two witnesses.

GEORGE B. SECHRIST.
